[57] CLAIM

The ornamental design for a table top water fountain with platform for decorative objects, as shown and described.

DESCRIPTION

FIG. 1 is a front perspective view of a water fountain showing my new design;

FIG. 2 is a rear elevational view thereof;

FIG. 3 is a top plan view thereof;

FIG. 4 is a bottom plan view thereof;

FIG. 5 is a left side elevational view thereof, the right side elevational view being identical; and,

FIG. 6 is a front elevational view thereof.

The cord is shown fragmented in FIGS. 3, 4 and 5 to indicate indeterminate length.
